DENNIS E. A. SAVOY, OF NEWCASTLE, NEW BRUNSWICK, CANADA, ASSIGNOR OF ONE-HALF TO GEORGE F. McWILLIAM, OF NEWCASTLE, PROVINCE OF NEW BRUNSWICK, CANADA.

AUTOMATIC FILLER.

Application filed July 21, 1921. Serial No. 486,652.

To all whom it may concern:

Be it known that I, DENNIS E. A. SAVOY, a citizen of the Dominion of Canada, and a resident of Newcastle, in the Province of 5 New Brunswick, Canada, have invented a new and Improved Automatic Filler, of which the following is a full, clear, and exact description.

This invention relates to improvements in 10 automatic fillers, particularly to an apparatus for measuring liquid as it is dispensed from a container and for automatically shutting off the flow of liquid after a pre-determined amount has been dispensed.

15 The primary object of the invention is to provide an apparatus of this character, which will obviate the necessity of store-keepers or other dealers in liquids standing by to measure liquid as it is dispensed and 20 turning off the flow after the desired amount has been drawn off from the receptacle.

Another object of the invention is to provide an apparatus of this character, which may be conveniently attached to various 25 forms of liquid containers, which will be simple and practical in construction, automatic in operation, durable and efficient in use, and comparatively inexpensive to manufacture.

30 With these and other objects in view, the invention consists in certain novel features of construction and combinations and arrangements of parts as will be more fully hereinafter described and pointed out in the 35 claims.

In the accompanying drawings:

Figure 1 is a view in elevation of my improved apparatus in its initial position;

Figure 2 is an edge view of Figure 1;

40 Figure 3 is a view similar to Figure 1, illustrating the position of the parts after a vessel has been filled;

Figure 4 is a top plan view of Figure 2; and

45 Figure 5 is a fragmentary view in transverse section on the line 5—5 of Figure 1.

Referring in detail to the drawings, 1 represents a liquid container, which is provided with a spout 2. A water outlet passage 3 in the spout is controlled by a sliding valve 4. A spring held lever 5 pivoted adjacent its intermediate portion on a bracket 6, carried by the spout is operatively connected to the valve 4, as indicated at 7 and 50 a contraction spring 8 connected to the free

end of the lever 5 normally retains the valve in closed position.

A bracket 9 secured to the outside of the container 1 rigidly supports a depending plate 10 in spaced relationship to the container. A yoke 11 pivoted to the bracket 9 is formed with an integral offset extension 12 engageable under the free end of the lever 5 to open the valve 4 against the tension of the spring 8. A graduated arm 13 is supported upon the yoke 11 upon a short depending extension 14 rigidly secured to the yoke. The arm 13 is provided adjacent its point of attachment to the yoke with a stop in the form of a lug 15. A weight 16 is mounted to slide or roll upon the arm 13, as indicated at 17.

A chain 18 depending from the yoke 11 is connected adjacent its intermediate portion to the free end of a lever 19, pivoted near its center on the lower extremity of the plate 10, as indicated at 20. The lever 19 is also provided with a weight 21 slideable thereon.

A rigid rod 22 includes an offset portion 23 at its upper end attached to the intermediate portion of the plate 10. The rod 22 is braced by any suitable braces such as 24. An arm 25 is provided at one end with a platform 26 and at its other end is pivotally connected to the lower end of the rod 22. The intermediate portion of the arm 25 is supported by the chain 18.

The operation of the apparatus is as follows:

The weight 16 is ordinarily at the inner end of the arm 13 and the valve 4 is normally held in closed position by the spring 8. When it is desired to draw off a pre-determined amount of liquid from the container 1, a vessel indicated in dotted lines at 27 is placed upon the platform 26 and the weight 21 is shifted on the lever 19 until it balances the weight of the vessel. This weight may be shifted without affecting the position of the arm 13 or weight 16 because of the flexibility of the chain 18. After the empty receptacle has balanced the weight 21, the weight 16 is moved on the arm 13 to the graduation representing the amount of liquid which is to be dispensed from the container. This movement of the weight 16 pivots the yoke 11, moving the extension 12 upwardly into contact with the lever 5 and opening the valve 4, as indicated in Figures 110

1 and 2. As the liquid runs from the container into the vessel 27 through the spout 2, the weight in the vessel 27 will gradually increase and by the time the desired amount has passed into the vessel, the weight of the vessel will preponderate over the balancing weight 16, the yoke 11 will be pulled downwardly, the weight 16 will slide to the inner end of the arm 13, the extension 12 will move out of the path of the lever 5, and allow the spring 8 to close the valve 4. After the vessel has been filled, it is removed from the platform and the weight 21 is adjusted to restore the platform to its normal position without affecting the position of the yoke 11 or arm 13. These parts will remain in the inclined or tilted position shown in Figure 3 until the weight 16 is again moved out upon the arm 13.

20 It will be noted that the extension 12 is limited in its movement in one direction by the spout 2 and in the other direction, it is stopped by the seating of the valve 4.

25 Although I have illustrated one of the preferred embodiments of my invention, it will be apparent that various slight changes and alterations might be made in the general form and arrangement of the parts described without departing from the invention and hence I do not wish to limit myself to the precise details set forth, but shall consider myself at liberty to make such slight changes and alterations as fairly fall 30 within the spirit and scope of the appended claims.

I claim:

1. The combination with a liquid container, an outlet spout, a spring held valve 40 controlling the flow of liquid through the spout, of a bracket secured to the exterior of the container, a plate rigidly depending from the bracket, a rigid depending rod fixed to the plate, a platform carrying arm 45 pivoted at one end to said rod, a yoke mounted to swing on the bracket, means integral with the yoke for positively opening the valve against the tension of the spring, a balancing arm carried by the yoke, a weight 50 slidable thereon, flexible means operatively connecting the yoke and the platform carrying arm.

2. The combination with a liquid container, an outlet spout, a spring held valve controlling the flow of liquid through the 55 spout, of a bracket secured to the exterior of the container, a plate rigidly depending from the bracket, a rigid depending rod fixed to the plate, a platform carrying arm pivoted at one end to said rod, a yoke mounted to swing on the bracket, means integral with the yoke for positively opening the valve against the tension of the spring, a balancing arm carried by the yoke, a weight 60 slidable thereon, flexible means operatively connecting the yoke and the platform carrying arm, a second balancing arm pivoted to the plate and connected to the flexible device adapted to compensate for the weight of an empty receptacle on the platform.

3. The combination with a liquid container, an outlet spout, a spring held valve controlling the flow of liquid through the spout, of a bracket secured to the exterior of the container, a plate rigidly depending from the bracket, a rigid depending rod fixed to the plate, a platform carrying arm pivoted at one end to said rod, a yoke mounted to swing on the bracket, means integral with the yoke for positively opening the valve against the tension of the spring, a balancing arm carried by the yoke, a weight 75 slidable thereon, flexible means operatively connecting the yoke and the platform carrying arm, means adapted to compensate for the weight of an empty receptacle on the platform.

4. The combination with a liquid container, an outlet spout and a spring held valve controlling the flow of liquid through 90 the spout, of a bracket secured to the exterior of the container, a plate rigidly depending from the bracket, a rigid depending rod fixed to the plate, a platform carrying arm pivoted at one end to said rod, a 95 yoke mounted to swing on the bracket, a lever controlling the valve, an extension on the yoke engageable with the lever for positively opening the valve against the tension of the spring, a balancing arm carried 100 by the yoke, a weight slidable thereon, and flexible means operatively connecting the yoke and the platform carrying arm.

DENNIS E. A. SAVOY.
